(57) **CLAIM**

The ornamental design for a contoured eyecup for a portable ophthalmoscope, as shown and described.

DESCRIPTION

FIG. 1 is a top perspective view of a contoured eyecup for a portable ophthalmoscope showing the contoured eyecup for a portable ophthalmoscope placed over a patient's eye;

FIG. 2 is a bottom perspective view of the contoured eyecup for a portable ophthalmoscope showing the contoured eyecup for a portable ophthalmoscope placed over a patient's eye;

FIG. 3 is a right side view of the contoured eyecup for a portable ophthalmoscope showing the contoured eyecup for a portable ophthalmoscope engaged with a portable ophthalmoscope and placed over a patient's eye;

FIG. 4 is a top view of the contoured eyecup for a portable ophthalmoscope showing the contoured eyecup for a portable ophthalmoscope engaged with a portable ophthalmoscope and placed over a patient's eye;

FIG. 5 is a top view of the contoured eyecup for a portable ophthalmoscope shown in FIG. 1;

FIG. 6 is a bottom view thereof;

FIG. 7 is a right side view thereof;

FIG. 8 is a left side view thereof;

FIG. 9 is a rear view thereof; and,

FIG. 10 is a front view thereof.

In the drawings, the broken lines depict unclaimed subject matter only and form no part of the claimed design.
